Patented Sept. 1, 1914.

UNITED STATES PATENT OFFICE.

AARON SCHNEIDER, OF PHILADELPHIA, PENNSYLVANIA.

BRAID-GUIDE FOR SEWING-MACHINES.

1,109,254.

Specification of Letters Patent.

Patented Sept. 1, 1914.

Application filed January 13, 1914. Serial No. 811,800.

To all whom it may concern:

Be it known that I, AARON SCHNEIDER, a citizen of the United States, residing at Philadelphia, in the county of Philadelphia 5 and State of Pennsylvania, have invented certain new and useful Improvements in Braid-Guides for Sewing-Machines, of which the following is a specification.

My invention relates to improvements in 10 braid guides for sewing machines, and more particularly to an improved construction of throat plate which is used when the machine is operated for underbraiding, that is to say securing soutache to the under face of the 15 goods by invisible stitching.

A further object is to provide improved 20 means for securing soutache to goods by a line of stitching extending through the goods and into the braid, but not extending through the soutache, so that the stitching is invisible from the right side of the goods on which the soutache is located.

A further object is to provide improvements of this character which dispense with 25 any necessity for guiding or holding the soutache as the latter follows the line of stitching, and a manipulation of the goods through the medium of the ordinary feed dog serves to guide the soutache and the latter is secured by invisible stitching extending 30 through the goods and into the soutache.

With these and other objects in view, the invention consists in certain novel features of construction and combinations and arrangements of parts as will be more fully 35 hereinafter described and pointed out in the claims.

In the accompanying drawings: Figure 1 is a perspective view illustrating my improvements. Fig. 2 is a plan view of my improved throat plate. Fig. 3 is a view in longitudinal section on the line 3—3 of Fig. 2 illustrating the braiding operation as it is carried out with my improved plate, and 45 Fig. 4 is a similar view in section on the line 4—4 of Fig. 2.

1 represents the arm of an ordinary sewing machine, and 2 the reciprocating needle bar movable in the head 3 and carrying a 50 needle 4 adapted to direct the needle thread 5 through an ordinary presser foot 6, and also through a needle opening 7, in my improved throat plate 8, which is secured to the bed plate 9 of the sewing machine, by screws 10. 55 It is to be understood that my improved

throat plate will be made to fit any ordinary sewing machine. It will, therefore, be necessary for the throat plate to be made in various sizes in accordance with the type of machine upon which it is used, and while I 60 have illustrated the throat plate as having a particular form of slot 11 through which the feed dog 12 projects, it is to be understood that the invention is not limited to this shape of slot as the plate will be made with 65 various forms of slot to suit various types of feed dogs in general use.

On the bottom of the plate 8, a guide 13 is secured. The guide 13 is provided with flanges 13^a at opposite sides having openings 13^b therein to receive screws 13^c which are screwed into threaded openings 13^d in the throat plate to removably secure the guide thereto. This guide constitutes a longitudinal channel communicating at one 75 end with an opening 14 in the plate 3, and its other end terminating short of the needle opening 7, so that the soutache indicated at 15 enters the opening 14, passes along the guide 13, and thence up through 80 the opening 17 as will be more fully herein-after explained.

The soutache 15 may be fed from any ordinary spool or bobbin 16, and a longitudinal slot 17 is formed in the plate 8 above 85 the guide 13, so that a pin or other suitable tool can be inserted through the slot to manipulate the soutache and position the same for use.

18 represents a piece of goods to which the 90 soutache 15 is to be sewed by an ordinary lock stitch formed by the needle thread 5 coöperating with a shuttle thread 19 as will now be explained.

The soutache 15 passes through the opening 14, thence along the guide 13 to the needle opening 7, and up through the needle opening 7 in contact with the goods 18. As the needle 4 reciprocates, it passes through the goods 18, and through the 95 soutache 15 at an angle to the longitudinal dimension of the soutache. In other words, as the soutache passes up through the opening 7, it will present to the needle 4 its longitudinal dimension, so that the needle while it extends through a portion of the soutache, does not extend transversely through the same, and as the soutache is sewed to the goods, it is connected by lines of stitching which extend only partially 100 105 110

therethrough, so that the stitching is invisible on the side of the goods to which the soutache is applied.

When the operation is begun, it is simply necessary to guide the goods, as the soutache follows automatically the line of stitching. The soutache is therefore accurately positioned on the goods by guiding the line of stitching, and as the stitching does not extend transversely through the soutache, any color of thread may be used with any color of soutache, and the soutache will be securely attached to the goods and not disfigured by the thread. With my improvements, therefore, I am enabled to attach soutache to the goods by an invisible stitch and carry out the operation rapidly and accurately. It is simply necessary to guide the goods as the machine compels the soutache to follow the line of stitching, and no attention need be paid to the soutache for its feed is entirely automatic.

While I have referred to the material used as soutache for the reason that my improvements are particularly adapted for use with such material, I do not limit myself thereto, but may use other kinds of braid, and hence I use the term "braid" in the claims as a generic term to include soutache or other material capable of attachment by my improvements.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. The combination with a sewing machine, of a throat plate having an opening therein through which a feed dog projects and is adapted to feed goods across the throat

plate, said throat plate having an opening therein through which the needle and the braid to be sewed are adapted to pass, said plate also having a longitudinal guide for braid leading to the needle opening in the plate and at an angle to the line of feed, substantially as described. 50

2. The combination with a sewing machine, of a throat plate having an opening therein through which a feed dog projects and is adapted to feed goods across the throat plate, said throat plate having an opening therein through which the needle and the braid to be sewed are adapted to pass, said plate also having a longitudinal guide for braid leading to the needle opening in the plate and at an angle to the line of feed, said plate having an opening over the guide, substantially as described. 60 65

3. The combination with a sewing machine, of a throat plate having a slot therein for the reception of a feed dog, said plate having a needle and a braid receiving opening adjacent the slot, and a braid receiving opening at a point removed from the needle opening, said plate having a guide at an angle to the line of feed and connecting the said openings, substantially as described. 70

4. The combination with a sewing machine, of a throat plate having a slot therein for the reception of a feed dog, said plate having a needle and a braid receiving opening adjacent the slot, and a braid receiving opening at a point removed from the needle opening, said plate having a guide at an angle to the line of feed and connecting the said openings, and said plate having a slot above the guide between the said openings, substantially as described. 80 85

In testimony whereof I have signed my name to this specification in the presence of two subscribing witnesses.

AARON SCHNEIDER.
